DESIGN FOR A COMBINED BRACKET AND LATCH FOR HAIR DRIERS

Andrew Madaras, Chicago, Ill.

Application December 18, 1939, Serial No. 88,997

Term of patent 14 years

To all whom it may concern:

Be it known that I, Andrew Madaras, residing at 1331 West Belmont Street, Chicago, in the county of Cook and State of Illinois, have invented a new, original, and ornamental Design for a Combined Bracket and Latch for Hair Driers, of which the following is a specification, reference being had to the accompanying drawing, forming part thereof, wherein

Fig. 1 is a perspective view of a combined bracket and latch for hair driers looking from the bottom and one side showing my design.

Fig. 2 is a perspective view looking from the bottom and the other side and

Fig. 3 is a perspective view looking down on the combined bracket and latch.

I claim:

The ornamental design for a combined bracket and latch for hair driers, as shown.

ANDREW MADARAS.
